Primary Examiner — Lucy Lieberman*(74) Attorney, Agent, or Firm* — Amster, Rothstein & Ebenstein LLP; Philip H. Gottfried, Esq.(57) **CLAIM**

The ornamental design for a watch band, substantially as shown and described.

DESCRIPTION

FIG. 1 is a top perspective view of a watch band showing my new design;

FIG. 2 is a bottom perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The depiction of the watch shown in dashed lines is for environment and does not form any part of the subject invention.
